UNITED STATES PATENT OFFICE

2,554,539

ADJUSTABLE LAMP MOUNT

James Lawrence Pettus, Sherman Oaks, Calif.,
assignor to Radio Corporation of America, a
corporation of Delaware

Application April 2, 1947, Serial No. 739,007

6 Claims. (Cl. 173—328)

1

This invention relates to optical systems and particularly to an adjustable mounting unit for a light source used in optical systems.

In many optical systems, such as those employed in recording sound photographically on film, the light source is usually a lamp having a substantially horizontal filament, the positioning of the filament with respect to the optical axis of the system being critical to provide a uniformly narrow beam of light across the sound track area. Adjustable mountings for such light sources have been used in the past to permit the filament to be placed on the optical axis of the unit and at a position which provides the maximum of light quanta to be focussed on the modulator and the most uniform distribution of the light over the area to be illuminated. Such a three way adjustable lamp mount is disclosed and claimed in Ross U. S. Patent No. 2,093,023, of September 14, 1937.

The present invention, however, is an improvement over the Ross construction, particularly for lamp light sources of sound recording systems or the exciter lamps of sound reproducing systems. The invention permits the less critical adjustments to be made during the construction of the mount which then may be permanently fixed while providing a simple and sensitive control for the critical adjustment which is generally necessary, particularly when lamps are changed.

To aid in positioning the filament of such a light source at the proper position with respect to the optical axis, pre-focus lamps are used, such a lamp having an aperture plate fixedly attached to the lamp base which positions the filament at a certain distance from the plate when the lamp is placed in its socket. However, the distance between the lamp filament and the pre-focussing plate is not uniform in all lamps and consequently a readily and accurately adjustable mount for the vertical position of the filament is required. This adjustment may also be made in the event a filament sags after it has been in use.

The principal object of the invention, therefore, is to facilitate the adjustment of a lamp light source in an optical system.

Another object of the invention is to provide an improved adjustable lamp mount.

A further object of the invention is to provide an improved lamp mount for simply and accurately adjusting the filament of the lamp in several directions.

A still further object of the invention is to 55 Referring now particularly to Figs. 2 and 3,

provide a lamp mount which provides a fine degree of adjustment of a lamp filament to align it with the optical axis of an optical system.

Although the novel features which are believed to be characteristic of this invention will be pointed out with particularity in the appended claims, the manner of its organization and the mode of its operation will be better understood by referring to the following description read in conjunction with the accompanying drawings forming a part hereof, in which:

Fig. 1 is a plan view of a lamp mount embodying the invention and shown in relation to the other optical elements of a sound recording system;

Fig. 2 is a cross sectional view of the invention taken along the line 2—2 of Fig. 1; and

Fig. 3 is a cross sectional view of the invention taken along the line 3—3 of Fig. 1.

Referring now to the drawings in which the same numerals identify like elements, the lamp mount of the invention consists of a casting 5 having approximately a circular configuration and extensions 6, 7 and 8. The casting is mounted in an opening in a base partially shown at 9. There are a pair of elongated slots 10 and 11 in casting 5 diametrically opposite one another and in which are a pair of screws 12 and 13, respectively, the slots also being wider than the shanks of the screws for a purpose explained hereinafter. A lamp 15 is shown in position in the mount, the lamp providing light flux for a sound recording optical system employing a lens 16, a modulating element such as a galvanometer 17, a noise reduction unit 18 and a film 19. The noise reduction unit 18 is disclosed and claimed in my copending application Serial No. 739,484, filed April 4, 1947, now Patent No. 2,452,322, issued October 26, 1948.

It is realized that to provide the proper illumination for the modulating mirror of the galvanometer 17 and the noise reduction unit 18, the filament 21 in the lamp 15 should be accurately aligned with the optical axis shown by the broken line 22. It is also necessary that the filament 21 be properly orientated with respect to the optical axis 22, that is, the axis of the filament should be normal to the optical axis.

It is also necessary that the filament be in the correct position along the optical axis to provide the maximum amount of light on the galvanometer mirror. The present invention provides all of these adjustments in a simple and efficient manner.

the casting 5 has a circular opening therein in which is inserted the lower portion 26 of a vertically adjustable member 25 which has its lower narrow portion 26 externally threaded and its upper and larger diameter section 27 externally threaded. The section 25 is keyed to the casting 5 by a key 29 to prevent relative rotation therebetween but permitting longitudinal, or axial adjustment therebetween. Positioned within the circular recess in the large diameter section 27 is an insulating collar 31 which is attached to the adjustable member 25 by two bolts 33 and 34. (See Fig. 3.) Also passing through the collar 31 at 90° from the bolts 33 and 34 are two more bolts 35 and 36 (see Fig. 2), the bolt 35 fastening an electrical contact spring 38, which has a contact element 39 at the end thereof and located in the center of the insulator 31, for making electrical contact with a center terminal 41 of the lamp 15. An electrical supply conductor may be connected to an electrical terminal 42 held in contact with the spring 38 by the bolt 35. Bolt 36 holds in position a top mounting plate or ring 44 to which another electrical conductor may be attached in any suitable manner, the plate 44 having an opening therein to permit the passage therethrough of the base 45 of the lamp 15.

Positioned under the ring 44 and between this ring and the spring contactor 38, is a second plate or ring 47 having an opening therein to accommodate the base 45 of the lamp 15 and which is mounted on three equidistantly spaced pins, two of which are shown in Fig. 2 at 49 and 50. These pins have enlarged upper ends 51 and 52 while surrounding the narrow portion of the pins are coil springs 54 and 55 which act to pull the ends 51 and 52 against the plate 44. The lamp 15 is provided with the usual pre-focus disc or ring 57 having three tapered holes 58 therein, the larger portions of the holes permitting the heads 51 and 52 of pins 49 and 50 to pass therethrough, so that the ring 57 can contact the plate 44. Now, if the lamp 15 is twisted, the narrow portion of the openings 58 will pass under the heads 51 and 52 of the bolts and the springs 54 and 55 will hold the lamp firmly in position, the contact terminal 41 of the lamp contacting the contactor 39 of the spring 38.

The pre-focus rings 57 are generally attached to the lamp bases 45 in such a manner that when adjusted in position under the pin heads, the filaments will always have the same spatial relationship. However, all lamps are not sufficiently uniform in all respects to completely avoid all adjustment and it, therefore, becomes necessary at times to slightly vary the lamp's position.

The less critical adjustments are those for varying the filament position along the optical axis and perpendicular to it and most lamps vary little in filament placement within the lamp. However, as mentioned above, these adjustments must be provided for, but can be made during construction. They are accomplished by loosening the screws 12 and 13 threaded into the base 9, and since the elongated holes 10 and 11 are wider than the shanks of the screws 12 and 13, a rotational adjustment of the casting 5 may be made on the base to bring the axis of the filament 21 perpendicular to the axis 22. To properly place the filament 21 along the optical axis, the casting 5 may be moved along the length of the elongated holes 10 and 11. With these two adjustments made the screws 12 and 13 may be tightened in the base to hold the lamp in these

two adjusted positions. Since these adjustments are only seldom required, the casting 5 may be doweled into position if desired by a pair of pin dowels 59 and 60 which pass into the base.

Also, as mentioned above, the critical adjustment, and the one required frequently, is in the vertical positioning of the filament 21 with respect to the plane of the optical axis 22. Variations in this position of the filament 21 are generally caused by the variations in the position of attachment of the ring 57 to the lamp base 45 between different lamps. Furthermore, a lamp filament may sag when heated or after hours of use. There is need, therefore, to frequently raise and lower the lamp 15 to accurately position the filament in the plane of the optical axis 22. This is accomplished with the present invention in a simple manner, but one which provides a fine and accurate control.

Referring again to Figs. 2 and 3, the longitudinally adjustable member 25 is held in position by a nut 62 threaded on its lower section 26 and which bears against a spring 63 which, in turn, bears against the casting 5. The other holding point for the member 25 is a ring 65 which is internally threaded to cooperate with the external threads of portion 27 of the member 25. The ring 65 has on its outer surface gear teeth which mesh with the teeth of a pinion gear 67. The ring is fitted in a recess in the inner surface of casting 5 to prevent longitudinal movement. The gear 67 is mounted in the extension 6 of the casting 5 and is rotatable when a shaft 68, on which it is mounted, is turned in any suitable manner, such as by a screw driver placed in a slot 69. Thus, to obtain vernier control of the vertical adjustment, it is only necessary to turn the shaft 68 and the member 25 will be raised and lowered with respect to the casting 5. Because of the small pitch of the threads between the portion 25 and the ring 65, these members are self-locking, particularly in view of the tension of the spring 63 which also prevents any backlash in the threads.

Extensions 7 and 8 are provided on the casting 5, for mounting optical elements such as a prism 71 on the end of a pin 72. The prism reflects light from the filament 21 to a monitoring screen to indicate the proper positioning of the filament 21 with respect to the optical axis 22.

The above mount is also provided with a releasing mechanism but since this construction is disclosed and claimed in S. E. Bartelson's co-pending application Serial No. 694,038, filed August 30, 1946, now Patent No. 2,471,190, issued May 24, 1949, it will be only briefly described herein. The releasing mechanism consists of a hand lever 75 in the form of a crank which extends under the plate 47. On the horizontal portion of the crank 75 are two extending rods or fingers 76 and 77, the ends of which may be forced upwardly against the plate 47 when the end of the crank is moved in one direction. When this occurs the plate 47 is moved upwardly against the tension of the springs 54 and 55 thus releasing the pressure of the heads 51 and 52 on the pre-focus ring 57 of the lamp. This permits the lamp 15 to be easily turned so that the large portions of the slots 58 are under the heads 51 and 52, thus facilitating the removal of the lamp 15 from the mount.

I claim:

1. An adjustable mount for a light source comprising a casting having an opening therein, a member rotatably fixed but axially adjustable in

said opening, a holder for a lamp positioned on the upper part of said member, said upper part being externally threaded, a ring threadedly interconnecting said externally threaded part, said ring having its opposite sides in contact with the sides of a groove in said casting to prevent an axial movement of said ring, and means geared to said ring for rotating said ring to axially adjust said member with respect to said casting.

2. A lamp mount in accordance with claim 1, in which said casting is provided with elongated holes to permit initial longitudinal and rotational translation of said casting.

3. A mount for permitting vernier adjustment of the filament of a lamp comprising a casting having an opening therein, a member positioned in said opening and adapted to be moved along the axis of said opening, means for preventing relative rotation between said casting and said member during axial movement of said member, means mounted within said member for supporting a lamp, a collar threaded to one end of said member, said collar having its sides in contact with the sides of a groove in said casting to prevent axial movement of said collar in any direction, a nut threaded in the other end of said member, a spring between said nut and said casting, and gear means for rotating said collar to move said member axially in either direction in said opening.

4. A mount in accordance with claim 3, in which a base is provided for said casting, together with means for attaching said casting to said base, said last mentioned means permitting ini-

tial movement of said casting with respect to said base within predetermined limits.

5. An adjustable mount comprising a casting having an opening therein, a rotatably fixed but axially movable member within said casting, a nut on one end of said member, a spring between said nut and said casting for tensioning said member to urge said member in one direction in said opening, a ring threaded on the other end of said member, said ring having its opposite sides in contact with the sides of a groove in said casting to prevent axial movement of said ring in any direction, means geared to said ring for rotating said ring and for moving said member in either of two directions in said opening, and means for providing for an initial longitudinal and rotatable adjustment of said casting.

6. An adjustable mount in accordance with claim 5, in which said last mentioned means includes tightening screws in oversized elongated holes in said casting.
